UNITED STATES PATENT OFFICE

150,467

DESIGN FOR A WHEELED TOY SNAIL

Harry Sebel, London, England

Application May 16, 1946, Serial No. 129,757

Term of patent 14 years

(Cl. D34—15)

To all whom it may concern:

Be it known that I, Harry Sebel, a subject of the King of Great Britain, residing at London, England, have invented a new, original, and ornamental Design for a Wheeled Toy Snail, of which the following is a specification, reference being had to the accompanying drawing, forming a part thereof.

Fig. 2 is a rear perspective view of the wheeled toy snail, showing my new design;

Fig. 3 is a rear perspective view of the wheeled toy snail shown in Fig. 1 on a reduced scale.

I claim:

The ornamental design for a wheeled toy snail, as shown.

HARRY SEBEL.
